CLAIM

The ornamental design for luggage, as shown and described.

DESCRIPTION

FIG. 1 is a front perspective view of luggage showing our new, original and ornamental design embodied therein, in accordance with the present invention;

FIG. 2 is a rear perspective view thereof;

FIG. 3 is a front elevational view thereof;

FIG. 4 is a rear elevational view thereof;

FIG. 5 is a top view thereof;

FIG. 6 is a bottom view thereof;

FIG. 7 is a first elevational side view thereof; and,

FIG. 8 is a second elevational side view thereof.

Any dash-dash broken lines in the drawings, including any dash-dash broken line over a claimed surface, represent unclaimed portions of the luggage and form no part of the claimed design.

1 Claim, 8 Drawing Sheets
